Primary Examiner — Elizabeth J Oswecki*(74) Attorney, Agent, or Firm* — Russell D. Nugent; The Humphries Law Firm, P.C.(57) **CLAIM**

The ornamental design for a hybrid boat and golf shoe, as shown and described.

DESCRIPTION

FIG. 1 is a top, left, front perspective view of a hybrid boat and golf shoe showing our new design;

FIG. 2 is a bottom, right, back perspective view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a front elevational view thereof; and,

FIG. 8 is a rear elevational view thereof.

FIGS. 1 and 3 illustrate a broken line striped pattern on the interior of the hybrid boat and golf shoe that form no part of the claimed design. All portions of the hybrid boat and golf shoe shown in broken lines form no part of the claimed design. FIGS. 1-8 illustrate a right hybrid boat and golf shoe, with the left hybrid boat and golf shoe being a mirror image thereof.

The broken lines shown in the drawings represent portions of the hybrid boat and golf shoe that form no part of the claimed design.
